UNITED STATES PATENT OFFICE.

IRVING T. SMITH, OF BROOKLYN, NEW YORK.

MAGAZINE TOY GUN.

SPECIFICATION forming part of Letters Patent No. 710,723, dated October 7, 1902.

Application filed July 17, 1901. Serial No. 68,644. (No model.)

To all whom it may concern:

Be it known that I, IRVING T. SMITH, a citizen of the United States, residing at Brooklyn, in the county of Kings and State of New York, 5 have invented certain new and useful Improvements in Magazine Toy Guns, of which the following is a specification.

This invention relates to magazine toy guns; and it has for its object to provide an 10 improved device of this class which will be pleasing and instructive in use and will effectually simulate in operation the operation of standard guns of this type.

This invention has for its further object to 15 provide an improved device of the class described which will be relatively simple in construction and not liable to get out of order.

In the drawings, Figure 1 is a side elevation 20 of a magazine toy gun constructed according to my invention. Fig. 2 is a central longitudinal sectional view of the device. Fig. 3 is a bottom plan view of the cylinder of the device, parts being in section.

Corresponding parts in all the figures are 25 denoted by the same reference characters.

Referring to the drawings, my improved magazine toy gun embodies a gun-barrel 1, provided with the customary bore 2, with which is associated a revolving cylinder 3, in 30 which the projectiles are carried and by which they are presented successively in position to be ejected into and through the bore 2. The gun also embodies means 4 for revolving the cylinder 3 and a spring-actuated hammer 5, 35 which is operated in the rotation of the cylinder 3 to successively discharge the projectiles from the cylinder into and through the bore 2.

In the preferred form of construction the 40 cylinder 3 consists of two cylindrical members 6 and 7, in which the projectiles 8, which may consist of shot, slugs, or other suitable bodies, and the cartridge or other firing media 9 are carried. The cylinders 6 and 7 are 45 provided each with an annular series of bores 9^a, the bores of which series are arranged in registration in the two cylinders, the arrangement of parts being such that upon joint revolution of the two members 6 and 7 of the cylinder 50 under one of the bores of the member 6 and one of the bores of the member 7 will be simultaneously brought into registration with

the bore 2 of the barrel 1. One of the members 6 and 7 may be provided with a key 10, which fits into a slot 11, formed in the other 55 member of the cylinder, so as to provide for joint revolution of the members 6 and 7 when one of said members is positively revolved by the operating means 4. The barrel 1 may be supported by a gun carriage or base 12, which 60 may consist of two outwardly-bowed legs or supports 13, which connect at their tops, as at 14, with the barrel 1 and the cylinder-shell 15 at one side of the same and are connected by a web 13^a. The two members 6 and 7 of 65 the cylinder 3 are carried rotatably in the cylindrical shell 15, the continuous sides 16 of which extend vertically and the front portion 17 of which connects at its edges with the inner end of the barrel 1, said front portion being provided with a suitable opening 17^a in registration with the bore 2. The casting or shell 15 may consist of a fixed half 18, which is firmly secured to the barrel 1, and a hinged half 19, which may be swung open to 70 permit removal of the cylinder 3. The rear edge portion of the continuous sides 16 of the shell or casing 15 is provided with an inwardly-projecting annular flange 20, forwardly of which the cylinder 3 is rotatably 75 supported. The two halves 18 and 19 of the shell or casing 15 may be provided at their meeting sides with securing means 21, arranged opposite the hinged portion 22 of the same and whereby the two parts of the shell 80 or casing may be secured together in operative cylindrical form.

The means for revolving the cylinder 3 may consist of a shaft 23, which is journaled in the supports of the gun and provided with a 85 gear 25, which meshes with an idler-gear 26, carried by a stud 27, supported rearwardly of the cylinder and meshing with an annular gear-rack 28, formed upon the rearward surface 29 of the rear member 7 of the cylinder 90 3. The hammer 5 is reciprocatingly mounted in a housing 30, which is carried by a brace 31, extending between the supports of the gun, and said housing 30 consists of a casing 32, in which the inner end of the hammer 5 95 is received, said hammer 5 being spring-actuated by means of a spring 33, which is interposed between the inner end of the hammer and the rear end 34 of the casing 32.

The hammer 5 is arranged to operate in the path of movement traversed by the cartridges 9 in the rear member 7 of the cylinder 3 and is operated in step with the revolution of the 5 cylinder by means of an annular cam device 36, which is secured to the rearward surface 29 of the member 7 of the cylinder concentrically with the same and inside of the gear-rack 28 and around the center of the member 7 of the cylinder. To this end the hammer 5 is provided with a laterally-projecting pin 37, which is depressed to retract or set the hammer 5 in alternation with the presentation of the several cartridges 9 in position 15 to discharge or project the projectiles 8 through the bore 2, and as each of said cartridges, with its respective projectile, comes into registration with the bore 2 the pin 37 slips from one of the shoulders of the cam 36 20 and engages with the respective cartridge 9 to fire the same.

It is manifest that the entire device as above described may be mounted in any suitable manner to obtain the desired trajectory 25 of the missiles discharged thereby, as is customary in standard guns of this type.

The operation and advantages of my improved magazine toy gun will be readily understood. The shaft 23 may be revolved by 30 means of a suitable crank 23^a, with which one end of said shaft is provided, and the revolution of said shaft serves to revolve the gears 25 and 26, and consequently to revolve jointly the two members 6 and 7 of the cylinder 3. This joint rotation of the members 35 6 and 7 of the cylinder brings the several registering openings of the two series of bores 9 successively into registration with the bore 2 of the barrel 1, so that upon the firing of 40 the cartridge 9 by means of the hammer 5 the respective missile 8 will be discharged through the bore 2 of the barrel 1. As the missile or projectile 8 in each of the bores 9^a in the member 6 of the cylinder comes into 45 registration with the bore 2 of the barrel 1 the pin 37 slips off from one of the shoulders of the circular cam 36 and by means of its spring 33 is actuated to engage operatively with the respective cartridge 9 and explode 50 the same to discharge the respective projectile 8. The gun is therefore automatically fired by operating the crank 23^a as many times as there are projectiles and cartridges in the cylinder 3, and when said projectiles 55 and cartridges have been exhausted the hinged half 19 of the shell 15 is opened up to permit the detachment of the two members 6 and 7 of the cylinder, which members may then be again reloaded and replaced within 60 the shell 15.

It is manifest that either the projectiles 8 or the cartridges 9 may be dispensed with in the use of the gun, according to the desired effects to be obtained, and when the cartridges 65 are dispensed with the hammer 5 may operate by direct contact with the projectiles

to discharge the same through the barrel of the gun.

The entire device is relatively simple in construction and may be operated and re-loaded very readily by children or other unskilled persons.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variation and modification as properly falls within the scope of my invention and the terms of the following claims.

Having thus described my invention, I claim and desire to secure by Letters Patent—

1. An improved magazine toy gun, comprising the barrel, a cylindrical shell arranged 90 at the inner end of the barrel and embodying a fixed portion and a hinged portion, a cylinder revolvably mounted in said shell and provided on its rear face with rearwardly-projecting teeth in two concentric rings, a gear meshing 95 with said outer ring of teeth for revolving said cylinder to successively present projectiles carried thereby in position to be discharged through the barrel, and a spring-actuated firing-pin adapted to be operated by the inner ring of teeth.

2. An improved magazine toy gun, comprising the carriage, a barrel, a cylindrical shell embodying a fixed portion mounted on said carriage and connected with the inner 105 end of said barrel and a hinged portion, a cylinder revolvably mounted in said shell and provided on its rear face with rearwardly-projecting teeth in two concentric rings, a gear carried by said carriage and meshing 110 with said outer ring of teeth for revolving said cylinder to successively present projectiles carried thereby in position to be discharged through the barrel, and a spring-actuated firing-pin carried by said carriage and 115 operated by the inner ring of teeth.

3. An improved magazine toy gun, comprising the barrel, a cylindrical shell arranged at the inner end of the barrel and consisting of two hinged members provided with inwardly-projecting flanges, a cylinder provided on its rear face with rearwardly-projecting teeth in two concentric rings and which fits within said cylindrical shell and is maintained in operative position by said flanges, 120 a hammer, means for revolving said cylinder to successively present projectiles carried by said cylinder in position to be discharged through the barrel, and means for actuating said hammer in the revolution of the cylinder.

4. In an improved magazine toy gun, a barrel, a cylindrical shell arranged at the inner

end of the barrel and consisting of two hinged members provided with flanges, a cylinder provided on its rear face with rearwardly-projecting teeth in two concentric rings and which fits within said cylindrical shell and is maintained in operative position by said flanges, and means for revolving said cylinder to successively present projectiles carried thereby in position to be discharged through

10 said barrel.

5. In an improved magazine toy gun, a barrel, a cylindrical shell arranged at the inner end of the barrel and consisting of two hinged members provided with flanges, a cylinder provided on its rear face with rearwardly-projecting teeth in two concentric rings and which fits within said cylindrical shell and is

maintained in operative position by said flanges, and means for revolving said cylinder to successively present projectiles carried thereby in position to be discharged through the barrel; said cylinder consisting of two interlocking cylindrical members or halves provided with registering series of bores arranged to be brought into registration with 25 the bore of the barrel.

In testimony whereof I have signed my name in the presence of the subscribing witnesses.

IRVING T. SMITH.
